UNITED STATES PATENT OFFICE.

JOSEPH H. McEVOY, OF HOUSTON, TEXAS.

STRAINING-PLUG.

No. 874,418.

Specification of Letters Patent.

Patented Dec. 24, 1907.

Application filed February 21, 1907. Serial No. 358,623.

To all whom it may concern:

Be it known that I, JOSEPH H. McEVOY, citizen of the United States, residing at Houston, in the county of Harris, State of Texas, have invented certain new and useful improvements in Straining-Plugs, of which the following is a specification, reference being had therein to the accompanying drawing.

10 This invention relates to a straining plug, and particularly to a form applicable to a pipe section used in liquid pumping by insertion in an aperture therein.

The invention has for an object to provide 15 a plug body having slits separated by intervening bars one face of each of which is spread laterally to reduce the width of said slits to the necessary degree of fineness for the straining action.

20 A further object of the invention is to provide a form of straining plug comprising a series of disks each having parallel straining slits in the head thereof together with a strengthening rim surrounding the disk in 25 order to retain them in contact and to provide the necessary strength of material for forcing the plug into the pipe section and prevent any distortion of the slits therein during such action as it is desirable to form 30 the disks of relatively light bendable material in order to facilitate the cutting of the slits in the disk and the subsequent swaging or closing thereof.

Other and further objects and advantages 35 of the invention will be hereinafter fully set forth and the novel features thereof defined by the appended claims.

In the drawing:—Figure 1 is a perspective of a cap plug embodying the invention; Fig. 40 2 is a similar view of this plug with the protecting rim; Fig. 3 is a vertical section through Fig. 2; Fig. 4 is a similar view showing a modified form of ring; Fig. 5 is a perspective of a cap plug having the slits thereof 45 extended only partially across the head; Fig. 6 is a cross section on the line 6—6, Fig. 5; Fig. 7 is a vertical section through a further modification; Fig. 8 is a similar view showing a further modification in which the 50 head of the cap is next the interior of the pipe; Fig. 9 is a perspective of a disk plug; Fig. 10 is a section on the line 10—10, Fig. 9; Fig. 11 is a perspective showing a plug slitted in opposite directions; Fig. 12 is a sectional 55 perspective showing a disk plug through

which the slits are broken; Fig. 13 is a section of a blank; Fig. 14 is a sectional perspective of the die and blank swaged thereon, and Fig. 15 is a section of a plurality of disk plugs disposed within a rim.

Like numerals refer to like parts in the several views of the drawing.

Referring to Fig. 1, the numeral 1 designates a cap plug the head of which is provided with a series of parallel straining slits 2 extending entirely across the same and separated by the bars 3 each of which is swaged or otherwise spread laterally as at 4 so as to reduce the width of the slit at the outer face of the plug thereby securing the necessary fineness for the straining action with a free clearance space directly at the rear of this face which will allow sand or other matter having a tendency to clog the strainer to be forced through the slits under pressure of the fluid, or by the pumping action and not be held between the bars thereby closing the slits and preventing a full flow.

In Figs. 2 and 3 the form of plug shown in Fig. 1 is provided with the strengthening rim 5 having an inwardly extending flange 6 against which the base of the plug will seat. This flange provides the necessary rigidity to the plug to permit its insertion in an aperture in the pipe under pressure without distorting or destroying the proper relation of the slits with each other or the diameter established at the point 4 thereof.

In Fig. 4 the plug shown in Fig. 1 is supplied with a modified form of ring 7 which is provided with the shoulder 8 to seat in the pipe aperture.

In Fig. 5 a cap plug is shown at 9, the head of which is provided with the flange 10 to seat in the pipe aperture, as shown in Fig. 6, and the slits 11 are only extended for a portion of the width of the head, while the intervening bars 12 are each spread upon their outer face, as at 13 to reduce the width of said slits at that point. In Fig. 7 a similar form of plug 14 is shown in which the flange 10 is omitted, and the bars 15 suitably spread to control the diameter of the slits extending between the same.

In the modification shown in Fig. 8, the spreading action of the bars 16 of the cap plug 17 there shown is upon the inner face, and the bars may be formed with grooves or depressions by which the spreading will be facilitated. In this form the wider or clear-

ance space of the slits is next the interior of the pipe 19 so as to facilitate cleaning thereof when necessary by a wire brush or swab.

The modifications shown in Figs. 9 and 10 illustrate a disk plug 20 provided with a series of parallel slits 21 and the separating bars 22 each of which is spread at its face 23 to govern the diameter of the slits as before described.

10 In Fig. 11 the plug 24 is provided with two series of slits 25 and 26 disposed at an angle to each other, the faces of the intervening bars 27 on the outer face being spread or swaged to secure the proper dimension of 15 slit.

Fig. 12 illustrates a disk plug 28 through which the slits 29 are punched or broken, the projecting edges 30 thereof being closed by pressure to determine the proper dimension 20 of the slits.

Figs. 13 and 14 illustrate a disk plug formed by a swaging die, the plug 31 in Fig. 13 being first punched with a straight slit 32 therein, this slit being tapered at one side and reduced to the proper diameter at the opposite side by means of a die 33 upon which the disk is compressed.

In Fig. 15 a modified form is illustrated in which a series of the disk plugs 31 are assembled within a rim 34 having the flange 35 and are thus held for insertion in a pipe section. When in such position the slits of the disk are preferably disposed in alinement.

It will be observed that in all of the applications of this invention the plug is adapted 35 to be made with slits or slots of a width greater than that intended for use, and by the spreading of the intervening bars the slits are reduced to the proper width for the 40 purpose desired. This is of particular importance as in the practical manufacture of such a plug it is difficult to cut the slit of the required narrowness and accuracy, and the invention permits stamping or punching of 45 the slits, and the subsequent finishing action by the spreading of the bars to reduce the width of the slits to the required narrowness and fineness at the entrance point of the material leaving the slits with a widened 50 charge portion extending in the direction of the flow therethrough, which effect a much

more desirable clearance and more uniform accuracy of slit than can otherwise be secured. With the use of the strengthening rim the disks can be formed of the necessary character and weight of material to facilitate this production by a punching or stamping operation and one or a number of such disks may be held within said rim and are thus supported or strengthened to permit their insertion into a pipe under pressure. The invention therefore presents a simple and efficient means for producing a straining plug having the proper diameter to prevent the entrance of extraneous material while effecting a free flow of the liquid therethrough.

Having now described my invention and set forth its merits, what I claim and desire to secure by Letters Patent is:—

1. A straining plug having a body provided with slits separated by intervening bars one face of each of which is spread laterally to form a pointed overhanging edge deflected from the plane of the side wall of the bar and approaching a similar edge upon a 75 parallel bar to reduce the width of said slits between the apices of the opposite edges.

2. In a well strainer, a cap plug comprising a plurality of disks each having a body provided with slits separated by intervening 80 bars one face of each of which is spread laterally to form a pointed overhanging edge deflected from the plane of the side wall of the bar and approaching a similar edge upon a parallel bar to reduce the width of said slits 85 between the apices of the opposite edges.

3. A straining plug comprising a plurality of slotted disks in contact with each other, and a strengthening rim surrounding said disks.

4. A straining plug comprising a plurality of slotted disks disposed with their slits in alinement, and a strengthening rim surrounding said disks and having an inwardly extending flange to engage the face of one 95 thereof.

In testimony whereof, I affix my signature in presence of two witnesses.

JOSEPH H. McEOY.
